UNITED STATES PATENT OFFICE.

ALBEN E. LUNDELL, OF NEW YORK, N. Y., ASSIGNOR TO WESTERN ELECTRIC COMPANY,
INCORPORATED, OF NEW YORK, N. Y., A CORPORATION OF NEW YORK.

TELEPHONE SYSTEM.

1,333,026.

Specification of Letters Patent.

Patented Mar. 9, 1920.

Application filed December 27, 1916. Serial No. 139,092.

To all whom it may concern:

Be it known that I, ALBEN E. LUNDELL, a citizen of the United States, residing at New York, in the county of Bronx and State of New York, have invented certain new and useful Improvements in Telephone Systems, of which the following is a full, clear, concise, and exact description.

This invention relates to telephone systems and particularly to the trouble indicating means employed in such systems.

The main feature of this invention is the provision of means whereby, if the apparatus associated with the operator's position is actuated and then does not proceed in its cycle of operation within a given time interval, a signal is actuated and the apparatus rendered unselectable until the abnormal condition has been remedied.

Other features of the invention will appear from the detailed description and claims.

The drawings, with Figure 2 placed above Fig. 1, and Fig. 3 placed above Fig. 2, represent diagrammatically a portion of a telephone system embodying the present invention.

The portion of the drawing at the right of the dotted line in Fig. 1, represents a controlling operator's position; the portion of the drawing at the left of the dotted line in Fig. 1, represents the terminals of a selector switch at a distant office.

Fig. 2 represents the arrangement of a trunk-finder switch, by means of which an operator's controlling circuit may be extended to indicator switches arranged to actuate certain signals.

Fig. 3 represents a plurality of variably operable number indicator switches of the sequence switch type adapted to be set by the controlling operator and also represents signals controlled by the switches for indicating the designation of a wanted line.

Fig. 4 represents the trouble indicating means and schematically shows the relation of this means to a group of trunk finders. The relation of the trouble indicating means represented within the large dotted rectangle B of Fig. 4, to the trunk finder diagrammatically shown in Fig. 2, is indicated by the small dotted rectangle at the bottom of Fig.

2. The relation of the means for rendering the group of trunks non-selectable shown in Fig. 5, to the dotted rectangle A of Fig. 4, to the por-

tion of the system herein disclosed, is indicated by the dotted rectangle A at the left of Fig. 1.

A plurality of sequence switches of a structure similar to that disclosed in Patent No. 1,127,808 to Messrs. Reynolds and Baldwin, and similar in operation and function to the sequence switch disclosed in the patent to McBerty, No. 1,125,579, are employed. The contacts controlled by any sequence switch are separated from the contacts of other sequence switches by dotted lines and by the confines of the drawings.

An allotter 200, Fig. 2, is of the same structure as the sequence switches employed in the system, and controls the contacts shown within the dotted rectangle around this allotter. Under the control of the allotter 200 the trunk finder 201 is preselected for service. The trunk finder may be of the same structure as the cord-finder fully described in Patent No. 1,168,319 to A. E. Lundell, or the selector switch disclosed in Patent No. 1,123,696, to Craft and Reynolds. The allotter 200 preselects the trunk finder 201 by moving the sequence switch 203, associated with such trunk finder, out of position 18 into position 1. The allotter will accomplish its preselecting operations when in its stopping positions indicated by the numerals adjacent to master contact 242. When the allotter is in position 4, into which position it is moved after the trunk finder associated with sequence switch 203 is taken for use, it will preselect one of a group of trunk finders whose sequence switches are in position 18. It will be noted that position 18 of the sequence switch associated with any trunk finder, is the position in which that trunk finder is awaiting preselection. The operation of the trunk finders similar to 201, and of the associated sequence switches similar to 203, are identical, and it is, therefore, deemed necessary only to describe the operation of the sequence switch 203 and trunk finder 201. The trunk finder 201, under the control of its associated sequence switch 203, may seize any one of a plurality of trunks over which a calling line has been extended to the operator's position shown in Fig. 3.

For brevity in disclosure, it has been assumed that the trunk, whose conductors are designated 101 and 129, terminates in terminals 130 and 156 of a selector switch (not shown) and that a fundamental circuit

including the well-known stepping relay (also not shown) is arranged to be connected to the terminals 130 and 156. A sender (not shown) which may be of the 5 type disclosed in Patent 1,168,319 to A. E. Lundell, is employed.

As soon as the connecting operator receives a call through trunks 101 and 129, the line relay 103 is energized over a circuit extending from grounded battery, contact 104, winding of line relay 103, contact 105, trunk 129, terminal 130, through the fundamental circuit established in extending the call to this operator's position, 10 terminal 156, trunk 101, contact 106, to ground. The line relay 103 attracts its armatures and at its right-hand armature and front contact completes a circuit from ground through conductor 107, contact 108, 15 magnet of sequence switch 100 to move this sequence switch out of position 1. As soon as sequence switch 100 reaches position 2, relay 207 is energized over a circuit extending from grounded battery, winding of this 20 relay, conductor 202, contacts 204 and 205, conductor 206, contact 109, to ground. The relay 207 attracts its armatures and at its right-hand armature and front contact completes a circuit for moving sequence switch 25 203 out of position 1 into position 2. This circuit may be traced from ground, right-hand armature and front contact of relay 207, contacts 208 and 209, magnet of sequence switch 203, to grounded battery. 30 When the sequence switch 203 passes through position 1₁, the energizing circuit, previously described, for the relay 207 is replaced by a circuit extending from grounded battery, winding of relay 207, contacts 204 35 and 210, resistance 263, back contact and armature of relay 211, to ground.

In position 2 of the sequence switch 203 the updriving clutch magnet 212 is energized over a circuit extending from grounded 40 battery, winding of magnet 212, conductor 213, contact 214, right-hand front contact and armature of relay 207, to ground. Under the control of this magnet the wipers of the trunk finder switch 201 are moved 45 upward over the bank of terminals containing one set of terminals for each trunk, to which the selector at the distant office (not shown), has access. Upon the engagement by the trunk finder wipers of the terminals 50 individual to the trunk disclosed in Fig. 1, an energizing circuit is established for the relay 211, which controls the stopping of the trunk finder switch. The energizing circuit for relay 211 may be traced from 55 grounded battery, winding of relay 211, contacts 215, 216, 217 and 218, to wiper 219, terminal 220, conductor 221, contact 110, to ground. Relay 211 then locks itself up over the circuit completed through contacts 215 60 and 216, front contact and armature 211, 65

to ground. As a result of the closure of this circuit, relay 211 remains locked up until the sequence switch 203 moves out of position 3. The energization of relay 211 70 interrupts at its armature and back contact the energizing circuit of relay 207. Relay 207 retracts its armature, and at its right-hand armature and front contact opens the operating circuit of the updriving magnet 212, if the wipers of the trunk finder have 75 been properly centered at the terminal of the switch, otherwise relay 207 will be maintained energized over a circuit extending from grounded battery, winding of relay 207, left-hand front contact and armature 80 of this relay, conductor 222, contact 223, conducting portion of commutator 224, commutator brush 225, to ground. When relay 207 deenergizes a circuit is completed for 85 moving sequence switch 203 into position 3. This circuit may be traced from grounded battery, magnet of sequence switch 203, conductor 226, contact 228, right-hand back contact and armature of relay 207, to ground. 90

In position 3 of sequence switch 203, a circuit is established from ground at the left-hand armature and front contact of relay 211, contacts 216, 229, conductor 230, wiper 231, terminal 232, conductor 233, contacts 111 and 112, conductor 113, magnet of sequence switch 100, to grounded battery, to move this sequence switch out of position 2 into position 3. Relay 103 is now maintained energized over a circuit extending 100 from grounded battery, contact 104, winding of relay 103, contact 114, left-hand armature and front contact of relay 103, contacts 118 and 119 over the fundamental circuit, above described. 105

In position 3 of sequence switch 100 a circuit is completed for energizing relay 207. This circuit may be traced from grounded battery, winding of relay 207, contacts 204 and 236, wiper 235, terminal 237, conductor 110 238, contacts 120 and 121, right-hand front contact and armature of relay 103, to ground. Relay 207 attracts its armatures and its right-hand armature and front contact completes a circuit from ground 115 through contacts 208 and 209, magnet of sequence switch 200, to grounded battery to move this sequence switch out of position 3 and into position 4.

With the allotter 200 in position 1, a circuit will be established from grounded battery, magnet of the allotter 200, contacts 239 and 240, contact 241, to ground. Under control of its master contact 242, the allotter is moved into position 4, in which 120 position it controls the preselection of another sequence switch associated with a trunk finder similar to 201. If this sequence switch is in position 18, which is its normal 125 position, a circuit is completed for moving 130

this sequence switch out of position 18 into position 1.

In position 4 of sequence switch 203 the energizing circuit for the relay 103 now extends from grounded battery, contact 104, winding of relay 103, contacts 114, 115, 116, conductor 117, terminal 234, wiper 243, conductor 244, contact 245, conductor 246, contacts 306, 307, 308, 309, 310, 311 and 312, conductor 313, brush 247, terminal 248, conductor 224, contacts 122 and 119, over the portion of the fundamental circuit mentioned, to ground at contact 106.

Also, in position 4 of the sequence switch 203 the number indicator 300 is operated. This circuit may be traced from grounded battery, magnet of indicator 300, contact 314, conductor 315, contact 249, conductor 250, left-hand armature and front contact of relay 207, conductor 202, contacts 204 and 236, brush 235, terminal 237, conductor 238, contacts 120 and 121, conductor 107, right-hand front contact and armature of relay 103, to ground. As indicator 300 is moving from position to position, its contact 316 is closed for each position passed, and in response to each closure of the contact 316, a shunt circuit for short-circuiting the stepping relay (not shown) is completed from relay 103. This circuit may be traced from grounded battery, contact 104, winding of relay 103, contact 114, left-hand armature and front contact of relay 103, contacts 118 and 122, conductor 224, terminal 248, wiper 247, conductors 313 and 317, contact 316, conductor 318, contact 251, right-hand front contact and armature of relay 207, to ground. As a result of the closure of this shunt circuit at contact 316, the stepping relay (not shown) of the fundamental circuit, above mentioned, becomes deenergized and actuates the counting relays in the well-known manner. After the indicator 300 has taken a number of steps determined by the operation of the sender (not shown), the counting relays will be actuated in the well-known manner to interrupt the fundamental circuit and cause the deenergization of relay 103. When relay 103 deenergizes it interrupts the energizing circuit of the relay 207.

With relay 207 deenergized, as soon as the indicator 300 reaches position X, a circuit is closed for moving sequence switch 203 into position 5. This circuit may be traced from grounded battery, magnet of sequence switch 203, contact 253, conductor 252, contacts 319, 320, 321, 322, 323 and 324, conductor 325, contact 254, conductor 255, right-hand back contact and armature of relay 207, to ground. In the meantime the fundamental circuit is again closed to energize the relay 103.

The fundamental circuit now extends from grounded battery, contact 104, winding of relay 103, contacts 114, 115 and 116,

conductor 117, terminal 234, wiper 243, conductor 244, contact 256, conductor 257, contacts 326, 307, 308, 309, 310, 311, 312, conductor 313, wiper 247, terminal 248, conductor 224, contacts 122 and 119, over that portion of the fundamental circuit previously mentioned. As a result of the energization of relay 103, relay 207 is again energized, and completes at its left-hand front contact and armature, an operating circuit for the indicator 301. This circuit may be traced from grounded battery, magnet of indicator 301, contact 327, conductor 328, contact 258, conductor 250, left-hand armature and front contact of relay 207, conductor 202, contacts 204 and 236, wiper 235, terminal 237, conductor 238, contacts 120, 121, conductor 107, right-hand front contact and armature of relay 103 to ground. The indicator 301 operates and at its contact 328 controls the operation of the sender (not shown). When the fundamental circuit is interrupted after the setting of this indicator, the relays 103 and 207 are deenergized. The deenergization of the relay 207 completes a circuit for moving the sequence switch 203 out of position 5 into position 6. This circuit may be traced from grounded battery, magnet of sequence switch 203, contact 259, conductor 258, contacts 329, 321, 322, 323, 324, conductor 325, contact 254, conductor 255, right-hand back contact and armature of relay 207 to ground. When the fundamental circuit is again reestablished to energize the relay 103, and in turn relay 207, an operating circuit is completed for the indicator 302, from grounded battery, contact 330, conductor 331, contact 260, conductor 250, left-hand armature and front contact of relay 207, conductor 202, contacts 204, 236, wiper 235, terminal 237, conductor 238, contacts 120 and 121, conductor 107, right-hand front contact and armature of relay 103 to ground. The indicator 302 controls at its contact 332 the operation of the sender (not shown). When the indicator 302 is properly set, the fundamental circuit is again interrupted to cause the deenergization of the relay 103, which in turn causes relay 207 to be deenergized. When the relay 207 deenergizes, a circuit is completed to move the sequence switch 203 out of position 6 into position 7. This circuit is established from grounded battery, magnet of sequence switch 203, contact 253, conductor 252, contacts 333, 322, 323, 324, conductor 325, contact 254, conductor 255, right-hand back contact and armature of relay 207 to ground. In position 7 of sequence switch 203 with relays 103 and 207 again energized on the reestablishment of the fundamental circuit, an operating circuit for the indicator 303 is established from grounded battery, magnet of indicator 303, contact 334, conductor 335, contact 261, conductor 250, 130

left-hand armature and front contact of relay 207, over the circuit previously described to ground at the right-hand front contact and armature of relay 103 to ground.

5 The indicator at its contact 336 controls the operation of the sender (not shown) as above mentioned. When the indicator 303 has been set in accordance with the operation of the sender, the fundamental circuit is

10 again interrupted, which results in the deenergization of relays 103 and 207. A circuit is thereupon completed for moving the sequence switch 203 into position 8, which circuit extends from grounded battery, magnet of sequence switch 203, contact 259, conductor 258, contacts 337, 323, 324, conductor 325, contact 254, conductor 255, left-hand back contact and armature of relay 203 to ground. In position 8 of the sequence

15 switch 203, with relays 103 and 207 again energized, an operating circuit for the indicator 304 is completed from grounded battery, magnet of indicator 304, contact 338, conductor 339, contact 262, conductor 250,

20 left-hand armature and front contact of relay 207 to ground at the right-hand armature of relay 103. The contact 338' of indicator 304 controls the operation of the sender (not shown). When the sender at

25 the close of this series of impulses interrupts the fundamental circuit, relay 103 deenergizes, and this in turn causes the deenergization of relay 207. When relay 207 deenergizes a circuit is completed to move sequence switch 203 out of position 8 into

30 position 9. This circuit may be traced from grounded battery, magnet of sequence switch 203, contact 253, conductor 252, contacts 339 and 324, conductor 325, contact

35 254, conductor 255, back contact and armature of relay 207, to ground. In position 9 of the sequence switch 203, the setting of the indicator 305 is accomplished in a manner similar to the setting of the other indicators mentioned. When the setting of indicator 305 is effected, the relay 103 deenergizes and this in turn causes the deenergization of relay 207.

50 After the setting of the indicator 305, a circuit is completed for moving the sequence switch 100 out of position 3 and into position 4. This circuit may be traced from grounded battery, magnet of sequence switch 100, conductor 113, contacts 112 and 122', conductor 123, terminal 280, wiper 281, conductor 282, contact 344, conductor 325, contact 254, conductor 255, back contact and right-hand armature of relay 207 to ground.

55 In position 4 of the sequence switch 100 a circuit is completed from grounded battery, contacts 124 and 125, winding of relay 126, conductor 127, winding of repeating coil 128, trunk conductor 129 and terminal 130 to ground at the preceding switch. Relay 126 attracts its armatures and completes

a circuit from grounded battery, contacts 124 and 125, winding of relay 126, contact 160, front contact and armature of relay 126, contacts 132 and 133, conductor 134, left-hand winding of relay 135 to ground. 70 Relay 135 attracts its armatures and at its right-hand armature and front contact establishes a locking circuit for itself from ground, its right-hand front contact and armature, contact 111 and 136, right-hand 75 winding of relay 135, conductor 137, contact 138 to grounded battery.

In position 9 of the sequence switch 203 an energizing circuit for relay 211 is also established from grounded battery, winding 80 of this relay, contacts 215 and 229, conductor 230, wiper 231, terminal 232, conductor 233, armature and front contact of relay 135, to ground. When relay 211 attracts its armature, it completes a circuit from 85 ground, its armature and front contact, contact 227, conductor 236, magnet of sequence switch 203, to grounded battery, to move sequence switch into position 10. In position 10 of this sequence switch, relay 207 is 90 energized over a circuit extending from grounded battery, winding of this relay, contacts 264 and 229, conductor 230, wiper 231, contact 232, conductor 233, armature and front contact of relay 135, to ground. 95 When relay 207 is energized, an energizing circuit for the relay 265 is completed from grounded battery, winding of this relay, contact 266, conductor 267, contact 297, conductor 250, front contact and armature of relay 207, contacts 264 and 229, conductor 230, to ground at the right-hand armature and front contact of relay 135. A substitute energizing circuit for relay 265 is completed as soon as sequence switch 203 reaches position 14, which circuit extends through contact 266, conductor 267, contact 341, conductor 342, contact 268, to ground. Relay 265 attracts its armature and completes a circuit from grounded battery, magnet of 100 sequence switch 203, contacts 269 and 270, front contact and armature of relay 265, contact 271, armature and front contact of relay 207, to ground, to move this sequence switch out of position 10 and into position 110 15. When sequence switch 203 leaves position 14 the lamp allotter 298 selects an idle set of indicators for use.

While the sequence switch 100 is in position 4, a circuit is completed from grounded 120 battery, contact 139, winding of relay 140, contacts 141 and 120, conductor 238, terminal 237, wiper 235, contact 236, contact 210, through resistance 263, back contact and armature of relay 211, (which is deenergized 125 when sequence switch 203 leaves position 9), to ground. The relay 140 attracts its armatures and at its left-hand armature completes a circuit from grounded battery, contact spring 142, contact 143, winding of re- 130

lay 103, contact 144, to ground. Relay 103 attracts its armatures, and at its left-hand armature and front contact completes a circuit from grounded battery, contacts 124 and 115, left-hand armature and front contact of relay 103, contacts 118 and 146, winding of relay 126, conductor 127, through trunk conductor 129, to ground, as previously described. Under this arrangement 5 relay 103 is maintained energized until the preceding selector is restored to its normal position. When the relay 103 attracted its right-hand armature it closed a circuit for moving the sequence switch 100 out of position 10 10 and into position 6. This circuit may be traced from grounded battery, magnet of the sequence switch 100, contact 108, conductor 107, right-hand front contact and armature of relay 103 to ground. The sequence 15 switch 100 is then moved out of position 6 by a circuit completed from grounded battery, magnet of the sequence switch 100, contact 180, back-contact and lower armature of relay 148 to ground. 20 25 When the operator inserts plug 147 into the jack (not shown), the sleeve relay 148 is energized over a circuit which extends from grounded battery, winding of relay 148, sleeve of plug 147, to ground at the 30 jack (not shown). Relay 148 attracts its armatures and completes a circuit for moving sequence switch 100 into a position to select the proper ringing current. 35 It will be assumed that the desired ringing current is applied in position 10 of sequence switch 100. The operating circuit for the sequence switch 100 may be traced from grounded battery, magnet of sequence switch 100, contact 149, left-hand front contact and armature of relay 135, which is locked up at this time, front contact and lower armature of relay 148, to ground. The sequence switch 100 continues to rotate until its operating circuit is interrupted 40 at the left-hand front contact and armature of relay 135; this occurs in the present instance when the contact 138 is opened in position 9 of sequence switch 100. In position 9 a circuit is completed from grounded battery, magnet of sequence switch 100, conductor 113, conductor 150, interrupter 151, contacts 152 and 153, front contact and lower armature of relay 148, to ground. In 45 position 10 of sequence switch 100, proper ringing current is applied to the selected party line. As soon as the relay 135 deenergizes an energizing circuit for the ringing relay 163 is closed from grounded battery, contact 131, contact and armature of relay 126, contacts 168 and 162, winding of relay 163, upper armature and back contact of relay 164, armature and back contact of the ring trip relay 165, left-hand back contact and armature of relay 135, lower front contact and armature of relay 148 to ground. 50 55 60 65

It will be noted that the relay 164 is shunted at this time. Relay 163 however, attracts its armatures to apply ringing current to the signal at the called substation. This circuit for applying ringing current, extends 70 through the left-hand winding of relay 165, contact 166, front contact and upper armature of relay 163, front contact and upper armature of relay 148, from the tip of the plug 147 to bell at the called substation, 75 through the ring contact of plug 147, lower armature and front contact of relay 163, contact 167 to ground. The ringing trip relay 165 is marginal and does not attract its armature until the called party answers, 80 at which time it does attract its armature and removes the short circuit about the relay 164. Relay 164 locks itself up and short-circuits the relay 163. 85

As soon as the locking circuit of relay 135 is interrupted it breaks at its right-hand front contact and armature the energizing circuit for the relay 207. As soon as the relay 207 deenergizes a circuit is completed 90 for moving sequence switch 203 out of position 15. This circuit may be traced from grounded battery, magnet of sequence switch 203, conductor 226, contact 228, right-hand back contact and armature of relay 207, to ground. At position 16 of sequence 95 switch 203 a circuit is completed for the down-drive magnet 272. This circuit may be traced from grounded battery, winding of magnet 272, contact 273, to ground. As soon as the commutator brush 274 reaches 100 normal segment 275 of the commutator, a circuit is completed from ground through commutator brush and normal segment 275, contact 276, conductor 226, magnet of sequence switch 203, to grounded battery. This circuit 105 drives the sequence switch 203 out of position 16. When the sequence switch 203 is moving through positions 16 and 17 the indicators 300 to 305 inclusive, are restored to their normal positions. The restoring 110 circuit for the indicator 300 may be traced from grounded battery, magnet of the indicator 300, contact 350, contact 286, conductor 255, right-hand back contact and armature of relay 207 to ground. The operating 115 circuit of the indicator 301 is completed through contacts 351 and 287 to ground at the armature of relay 207. The indicator 302 has its restoring circuit closed through contacts 352 and 288 to ground. In like 120 manner, the indicators 303, 304 and 305 have their operating circuits closed to ground, through contacts 281, 290 and 291 respectively. As soon as all of the indicators are restored to their normal position, a circuit 125 for moving the sequence switch 203 out of position 17, is completed from grounded battery, magnet of sequence switch 203, contact 277, conductor 278, through the normal contacts 342, 320, 321, 322, 323 and 324, con- 130

ductor 325, contact 254, conductor 255, right-hand armature and back contact of relay 207, to ground. Position 18 is the normal position of the sequence switch 203 in which it awaits selection. As soon as the allotter 200 reaches position 1, a circuit is completed from ground through contacts 241, 240 and 209, magnet of sequence switch 203, to grounded battery, which moves this sequence switch into position 1.

The apparatus associated with the operator's position, indicated at Fig. 3, is restored to normal when the relay 126 is deenergized by reason of the interruption of its energizing circuit at the preceding selector switch. When relay 126 retracts its armature, the relay 140 deenergizes and this in turn causes the deenergization of the relay 103. When relay 103 retracts its armature a circuit is completed for moving the sequence switch 100 to its normal position, which circuit may be traced from grounded battery, magnet of sequence switch 100, contact 152, right-hand back contact and armature of relay 103, to ground.

It will be understood in this system that a trunk finder similar to 201 is normally in position 1, selected for use, and a second trunk finder similar to 201 is in position 18 awaiting selection. If, however, due to any abnormal operation of the trunk finders, one or more trunk finders are in position 18 in which they are awaiting selection and no trunk finders are standing in position 1, a circuit arrangement disclosed in Fig. 4 becomes effective. This condition may arise from failure of any trunk finder to proceed in its cycle of operation from position 1 to position 4 of its sequence switch, in which position the allotter 200 operates to select an idle trunk finder. The circuit arrangement of Fig. 4 under the control of a timing device, operates an alarm to indicate the improper operation of the trunk finders and applies ground to the test terminals of the selector switch at the distant office so that the trunks leading to the operator's position shown in Fig. 3, cannot be selected until the abnormal condition has been removed.

In this system a switchboard clock 400 opens and closes the contact 401 at regular intervals of time. When contact 401 is closed through the operation of the switchboard clock the relay 402 is energized over circuit extending from grounded battery, winding of magnet 402, contact 401, to ground. Relay 402 attracts its armatures and thereby completes a circuit from grounded battery, front contact and armature of relay 402, armature and back contact of relay 403, resistance 404, winding of relay 405, to ground, at one of the contacts 406, 407, and 408, one of such contacts being associated with and controlled by one of the trunk finders in the group. Relay

405 attracts its armature and thereby completes a locking circuit for itself from grounded battery through its armature and front contact, winding of relay 403, resistance 404, winding of relay 405, to ground at one of the contacts 406, 407 and 408. Relay 403 attracts its armature. When relay 402 again attracts its armature a circuit is completed from grounded battery, front contact and armature of relay 402, armature and front contact of relay 403, winding of relay 409, winding of relay 410, to ground. Relay 409 attracts its armature and completes a locking circuit for itself from grounded battery, armature and front contact of relay 405, armature and front contact of relay 409, winding of relay 409, winding of relay 410, to ground. The relay 410 attracts its armature and completes a circuit for energizing relay 411, which circuit may be traced from grounded battery, winding of relay 411, front contact and armature of relay 410, to ground. Relay 411 when energized closes an energizing circuit for relay 414 and this relay controls a local circuit for alarm 413.

The means for applying ground to the test terminals of the trunks comprises a switch which may be termed "a snap switch." This switch is similar to the structure of the sequence switches, previously mentioned, with the exception that it has only two operating positions. These positions are the normal position of the switch and a second position in which it remains to apply ground to test terminals, until an attendant removes the abnormal conditions and resets the switch. When relay 410 attracted its armature a circuit for actuating switch 412 was established from grounded battery, magnet of switch 412, contact 419, front contact and armature of relay 410.

If, however, one of the sequence switches associated with one of the trunk finders of the group moves into position 1, subsequent to the energization of relay 405 but prior to the second energization of relay 402, the relay 405 will be short-circuited in the following manner to prevent the operation of the alarm and to prevent the grounding of the test terminals of the mentioned group of trunks. In this instance relay 405 is short-circuited by way of conductor 415 through any of the contacts 416, 417 or 418 to ground. Relay 405 retracts its armature and thereby interrupts the energizing circuit of relay 403. When relay 403 retracts its armature, the operating circuit of relay 409 is opened. The deenergization of relay 409 causes relay 410 to deenergize to prevent the operation of the alarm and the grounding of the test terminals of the mentioned trunks.

It will be understood that these circuits and apparatus may be arranged to become effective if there is no trunk finder in po-

sition 1 during a predetermined interval, regardless of whether other trunk finders are in position 18.

What is claimed is:

- 5 1. In a telephone system, telephone lines, an automatic switch associated with said lines, means for indicating the failure of said switch to function properly, and means to render said telephone lines unselectable when said switch fails to function properly.
- 10 2. In a telephone system, a plurality of telephone lines, a plurality of automatic switches arranged to be brought into operative relation to any one of said lines, means common to said switches for indicating the failure of any switch to function properly, and means to render said lines unselectable when any switch fails to function properly.
- 15 3. In a telephone system, a plurality of telephone lines, a plurality of switches associated with said telephone lines, mechanism for allotting a switch for use, means for indicating the abnormal operation of said switch, and means to characterize said lines by an unselectable condition when any of said switches fail to function properly.
- 20 4. In a telephone system, a plurality of telephone lines, a plurality of switches associated with said telephone lines, mechanism for allotting a switch for use, means for indicating the failure of any switch to be allotted during a predetermined interval while any switch is in its normal position, and means to characterize said telephone lines as busy when said indicating means operates.
- 25

ciated with said telephone lines, mechanism for allotting a switch for use, means for indicating the failure of any switch to be allotted during a predetermined interval, and means to characterize said lines with an unselectable condition when any of said switches fail to function properly.

30 5. In a telephone system, a plurality of telephone lines, a plurality of switches each having a normal position, mechanism for allotting a switch for use, means for indicating the failure of any switch to be allotted during a predetermined interval while any switch is in its normal position, and means to characterize said telephone lines as busy when said indicating means operates.

35 6. In a telephone system a plurality of telephone lines, a plurality of switches, mechanism for allotting a switch for use, means for indicating the failure of any switch to be allotted during a predetermined interval, and means for rendering said telephone lines unselectable when no switch has been allotted for use.

40 In witness whereof I hereunto subscribe my name this 26th day of December, A. D. 1916.

ALBEN E. LUNDELL.
